ASSIGNORS TO EDWARD N. WHITE, J. LEWIS WYCKOFF, AND JAMES M. EATON,
TRUSTEES, ALL OF HOLYOKE, MASSACHUSETTS.

PLATFORM.

Application filed August 17, 1921. Serial No. 493,052.

To all whom it may concern:

Be it known that we, EDMUND TOMLINSON and RICHARD T. GIFFORD, citizens of the United States, residing at Springfield, in the 5 county of Hampden and State of Massachusetts, have invented new and useful Improvements in Platforms, of which the following is a specification.

This invention relates to improvements in 10 transferable load supporting platforms commonly known as platform skids of the type used, in connection with a system of trucking wherein elevating trucks are employed to transport materials supported or carried 15 by these platforms.

Platforms of the general character to 20 which the present invention relates usually comprise a substantially flat, wooden platform that is supported from the floor by wooden girders arranged in spaced relation beneath the platform to hold the platform a sufficient distance from the floor to allow an elevating truck to be placed thereunder for the elevating of the platform and the load 25 carried thereby.

This system of trucking has brought about 30 the development of trucks that have a capacity for transporting extremely heavy loads and the platforms in use are not sufficiently strong or otherwise adapted to withstand the heavy duty required of them in transporting the loads conveniently handled by the trucks.

One object of the present invention is the 35 provision of an improved platform that possesses the rigidity and strength necessary to withstand the hard usage to which they are subjected. Another object is the provision of a platform, that while it is strong and 40 rigid in construction, is also comparatively light in weight in itself and which may be economically manufactured.

To this end the invention consists in the 45 novel construction, combination and arrangement of parts hereinafter described and more particularly pointed out in the appended claims. The invention will be readily understood by reference to the accompanying drawings which for descriptive purposes 50 illustrate the present preferred embodiment of the invention.

In the drawings,—

Fig. 1 is a perspective view of the platform comprising our improved structure.

Fig. 2 is a fragmentary view on a larger 55 scale showing the connection of the tie members, load support and feet.

The platform 1 preferably comprises a plurality of transverse load supporting members 2, that may be of any width or length 60 desired, depending upon the use for which the platform is to be adapted. These members 2 are preferably arranged so that their adjacent edges are in a closely abutting relation to provide a load support having a 65 comparatively even or smooth load supporting surface. While we have shown merely for illustrative purposes a load support comprising a plurality of separate members in close adjacency it is obvious that under cer- 70 tain conditions it may be desirable to employ a plurality of comparatively narrow members arranged in a spaced relation to form a latticed support, or under other conditions it may be desired to use a load sup- 75 port consisting of a single member.

Tie members 3 for supporting the before mentioned supporting members and for tying them in their proper relation are provided and preferably comprise angle bars of 80 metal that have depending flange portions 4 and horizontal portions 5 as shown. The members 3 are preferably arranged in a spaced parallel relation adjacent opposite ends of the load supports. 85

Supporting feet 6 that are in the shape of a U for supporting the structure are provided and preferably comprise integral top portions 7 and vertical web portions 8 that are connected by the sides 10 and 11 to the 90 horizontal foot portions 9. Suitable openings are provided in the portions 7 and 8 of the feet for securing the feet, tie members and load support in a rigid relation.

While we have shown the supporting feet 95 located at opposite ends of the tie members it is obvious that they may be moved to various locations along the members 3 depending upon the use for which the platform is to be employed.

Bolts 13 having their head portions preferably countersunk or flush with the load 100

support 2 pass through suitable openings in said load support and in the horizontal portions 5 of said tie members and in the top portions 7 of said feet to securely hold the 5 load supporting member 2, tie members 3 and feet 6 together. Additional bolts or rivets 13' also pass through depending portions 4 of the tie members 3 and web portions 8 of the feet which together with the 10 bolts 13 secure said parts rigidly in intertrussed relation. The load support 2 throughout the remainder of its length is also preferably secured to the horizontal portions of the tie members 3 by bolts 14 as 15 shown.

Thus it may be seen that the before described structure furnishes a platform that is rigid in construction and that possesses the maximum of strength and durability and by 20 the rearrangement or relocation of the parts it may be adapted for use in connection with the transporting of various materials or with various types of trucking equipment.

While we have described the invention in 25 the form at present preferred it will be understood that various changes may be made in this construction without departing from the scope of the invention.

What we claim is—

30 1. A transferable platform comprising in combination, a load support, longitudinal tie members adjacent each lateral edge of said load support each of which is provided with a horizontal portion secured to said 35 load support and a depending flange portion, U shaped supporting legs for said platform mounted adjacent the tie members each of which has a horizontal foot portion and side portions connected at their upper ends 40 by an integral top portion, a vertical web portion connecting the top and side por-

tions of said leg adjacent the upper end thereof, and means for rigidly securing each leg to the adjacent tie member and load support.

2. A transferable platform comprising in combination, a load support, longitudinal tie members adjacent each lateral edge of said load support and a depending flange portion, U shaped supporting legs for said platform mounted adjacent the tie members each of which has a horizontal foot portion and side portions connected at their upper ends by an integral top portion, a vertical web portion connecting the top and side portions of said leg adjacent the upper end thereof, and means for rigidly securing the leg top portion horizontal portion of the tie member and load support together. 60

3. A transferable platform comprising in combination, a load support longitudinal tie members adjacent each lateral edge of said load support, each of which is provided with a horizontal portion secured to said load support and a depending flange portion, U shaped supporting legs for said platform mounted adjacent the tie members each of which has a horizontal foot portion and side portions connected at their upper ends by an integral top portion, a vertical web portion connecting the top and side portions of said leg adjacent the upper end thereof, means for rigidly securing the leg top portion, horizontal portion of the tie member and load support, and means for securing the vertical web portions of the legs to the depending flange portions of the tie members. 70

In testimony whereof we have affixed our signatures.

EDMUND TOMLINSON.
RICHARD T. GIFFORD.
